HUMMINGBIRD FEEDER

Rocco Calamia, La Mirada, Calif.
(930 S. Ajax Ave., City of Industry, Calif. 91744)

Filed Jan. 31, 1975, Ser. No. 545,820

Term of patent 14 years

Int. Cl. D30—03

U.S. Cl. D30—15

FIG. 1.

FIG. 2.

FIG. 3.

FIG. 4.

FIG. 1 is a perspective view of a hummingbird feeder showing my new design;

FIG. 2 is a side elevational view, the opposite side being a mirror image thereof;

FIG. 3 is a top plan view; and

FIG. 4 is a bottom plan view.

I claim:

The ornamental design for a hummingbird feeder, substantially as shown and described.
